US00D764010S

(12) **United States Design Patent**
Tian et al.

(10) **Patent No.:** **US D764,010 S**
(45) **Date of Patent:** **** Aug. 16, 2016**

(54) **ANIMAL TRAP**

(71) Applicant: **J.T. Eaton & Company, Inc.**,
Twinsburg, OH (US)

(72) Inventors: **Daofeng Tian**, Zaoyang (CN); **Qi Jin**,
Tainmen (CN)

(73) Assignee: **J.T. Eaton & Company, Inc.**,
Twinsburg, OH (US)

(**) Term: **14 Years**

(21) Appl. No.: **29/518,138**

(22) Filed: **Feb. 20, 2015**

(51) LOC (10) Cl. **22-06**

(52) U.S. Cl.

USPC **D22/119**

(58) **Field of Classification Search**

USPC D22/119-124; 43/58, 70, 81, 88-89,
43/91, 96-97

CPC A01M 23/26; A01M 23/30
